UNITED STATES PATENT OFFICE.

FRED D. FOWLER, OF WATERTOWN, MASSACHUSETTS, ASSIGNOR TO HOOD RUBBER COMPANY, OF WATERTOWN, MASSACHUSETTS, A CORPORATION OF MASSACHUSETTS.

STRAIGHT-SIDE BEAD FLAPPING MACHINE.

Application filed January 19, 1924. Serial No. 687,396.

To all whom it may concern:

Be it known that I, FRED D. FOWLER, a citizen of the United States, and resident of Watertown, in the county of Middlesex and 5 State of Massachusetts, have invented certain new and useful Improvements in Straight-Side Bead Flapping Machines, of which the following is a specification.

My present invention relates to improvements 10 in machines for applying rubberized covering strips to bead core rings, such as are incorporated in the edges of open bellied or double tube pneumatic tires, and is herein shown as embodied in apparatus intended 15 for applying such strips to cores intended for straight side or inextensible edge tires, such cores embodying metal strengthening means, such as braided wire, and being in stiff or relatively inflexible hoop or ring 20 form.

The invention aims to provide a relatively simple, economical and durable form of apparatus which will expeditiously apply the strips in a proper manner, while maintaining the ring in a horizontal plane in convenient position and with the flap uppermost and exposed throughout to observation of the operator.

With these and other objects in view, the 25 invention includes the novel features of construction and arrangement and combination of parts hereinafter described, and particularly defined by the appended claims.

An embodiment of my invention is illustrated in the accompanying drawings, in which—

Figure 1 is a side elevation of a machine constructed in accordance with my invention.

40 Fig. 2 is a plan view.

Fig. 3 is a detail view of the first guide roll.

Fig. 4 is a detail view of the fabric supporting drum and cooperating applicator or 45 presser roll.

Fig. 5 is a detail view of the second guide and fabric forming roll.

Figs. 6, 7 and 8 are detailed views showing the succeeding pairs of rolls and the 50 manner in which they cooperate.

Figs. 9 and 10 are detail views of the driving mechanism.

55 Referring by reference characters to these drawings, the numeral 1 designates a table or platen which is mounted upon suitable

standards 2, preferably of pipe formation, connected adjacent their lower ends by horizontal brace members 3 by means of T couplings 4.

The table is located at a height convenient 60 to the operator and is provided with guiding means for the fabric covering strip, which means preferably takes the form of a pair of parallel guides 5 adjustably held to the table by means of thumb screws 5^x passing through elongated openings or slots in the laterally projecting portions 5^a of the guide bars 5, whereby the guides may be adjusted towards or from each other for properly positioning the fabric and to accommodate varying widths according to the size bead being wrapped. The fabric strip may be conducted from any suitable source of supply (not shown) and after traveling 65 along the table between the guides, passes underneath and upward around an idle guide roller 6, and thence upward around supporting drum 7, both the guide roller and drum being journaled in the brackets or standards 8 bolted to the table.

The drum is provided with peripheral flanges 7^a forming guides for the edges of the strips and to accommodate different size strips these flanges are made adjustable towards and from each other. To this end the drum is threaded for a suitable distance from opposite ends and the flanges are in the form of split internally threaded rings, the ends of which are held together by set screws, which may be loosened to allow the 70 flanges to be screwed in or out, and tightened to clamp them firmly in position. The central unthreaded portion of the drum is designed to support the fabric at the point where it contacts with the bead core.

These bead cores 9 are approximately triangular in cross section and I have found the best results are secured by juxtaposing the bead core and fabric 10 in such a manner that the edge 9^a is pressed against the strip at approximately the center line thereof and thereafter the margins of the strip manipulated in the manner hereinafter described.

Adjacent the drum 7 but in advance thereof, is journaled a bead core guide and 105 positioning roll 11 which is located with its upper peripheral portion in substantially horizontal alignment with the upper portion of the drum. This guide has a channel to receive the bead core which is formed by a 110

pair of flanges 11^a and 11^b, the flange 11^b being adjustable to adapt the roll to cores of various sizes, preferably by making the flange in the shape of a ring having internal 5 threads engaging corresponding threads on the roll 11. The roll is journaled on a rod or arm 12 which is adjustably carried by the split upper end of a bracket member 13 which in turn is mounted for vertical ad- 10 justment on a post 13^a conveniently by forming the lower end of the bracket of split tubular form to slidably engage this post, and providing it with an encircling (taper) clamping nut for compressing or contract- 15 ing the split end on the post. By this means the guide roll is capable of both vertical and horizontal adjustment relative to the fabric supporting drum.

Upon the opposite side of the drum is a 20 second core guide and fabric forming roll 14 rotatably mounted upon an arm 15 se- cured for horizontal adjustment to the split upper end of a bracket 16 carried by a post 16^a similar to post 13^a.

25 The bead core having been guided by the roll 7 so that its edge 9^a is positioned centrally of and upon the fabric, it is pressed thereagainst and caused to adhere thereto by a presser or applicator roll 17 (Fig. 4) 30 journaled on an arm 18 which is adjustably carried by a split bracket 19 capable of being clamped to the arm by clamping screw 19^a. Bracket 19 is pivoted in the forked or bifurcated upper end of a second bracket 35 member 20 adjustably mounted on a post 21, the bracket being split and provided with a clamping screw 20^a by which it may be firmly secured at any desired elevation. The roll 17 when in applying position, as shown 40 in Fig. 4, is pressed yieldingly against the upper face of the core by a spring 22 hav- ing one end fast to bracket 19 and the other end to a part of bracket 20.

The rear extremity of arm 18 is provided 45 with a handle 18^a by which the roll 17 may be swung away from the drum to permit re- moval of the covered core and its replace- ment by a fresh one. The relative arrange- 50 ment of pivot and spring connection is such that when the arm 18 is swung back to the limit of its movement, the spring lies in rear of the bracket pivot, or in other words, crosses the dead center, and holds the appli- cator roll 17 away from the bead core. 55 After the bead has been pressed against and caused to adhere to the fabric, these both pass to the roll 14 which has side flanges corresponding approximately to the two sides of the bead and which deflect the mar- 60 gins of the fabric strip upwardly, as shown in Fig. 5.

After leaving roll 14 the assembled core and strip pass between a pair of coacting rolls 23 and 24, by the action of which the 65 fabric is pressed into intimate contact with,

and firmly united to, two sides of the core, as shown in Fig. 6. Roll 23 is mounted on a shaft 25 journaled in bearing bracket 26 carried by the table, and said roll is made in two parts, the one to which the reference 70 character 23 is applied being fast on the shaft, and the other designated 23^a being removable conveniently by screw threading it onto a projecting end of the shaft. Roll por- 75 tion 23 has a vertical face corresponding to the vertical face of the core, while roll portion 23^a has a face curved to fit the correspond- ing core face, this being of somewhat a re- 80 verse curve. By removing member 23^a and substituting one of a different size or shape, 80 the variations in cores may be accommodated.

The roll 24 is mounted upon a swinging 85 bracket and spring pressed in a manner ex- actly similar to roll 17, and as this will be 90 obvious from the drawing, repetition of the description is deemed unnecessary. Roll 24 has a peripheral rounded flange 24^a de- 95 signed to press upon the slightly concave upper surface of the core, and a partly 95 spherical head 24^b which acts to hold the corresponding marginal flap of the fabric strip deflected outward away from the other flap, this being rendered necessary by the fact that said flap projects from the vertical 95 face of the core.

The next operation is to deflect or fold the marginal flap 10^a across the upper face of the bead and over the other flap 10^b and this is accomplished by a stitching roller 27 100 journaled upon a spring pressed swing arm 27^a similar to those already described, roller 27 being journaled, however, upon an axis slightly inclined from the vertical and hav- 105 ing a flat under face and peripheral flange which enlarges said face without unduly enlarging the roll body.

The final action is performed by a pair 110 of coacting rolls 28 and 29, 28 being a two part roll similar to roll 23, but its remov- able part 28^a being provided with a portion 28^b of truncated cone shape designed to sup- 115 port the flap 10^b in inclined position against the pressure of coacting roll 29 which is of cylindrical formation. This roll is mounted on a swinging spring pressed arm similar to those already described and overlies not only the roll portion 28^b but the adjacent portion of the bead core, whereby not only are the two flaps pressed into intimate con- 120 tact, but the flap 10^a is pressed firmly against the thin edge of the bead.

The various rolls hereinbefore described are arranged on the arc of a circle in a hori- 125 zontal plane, whereby the flapped edge of the bead ring is kept uppermost and out- wards towards the operator, and he is en- abled to watch the progress of the work at all times.

The portion of the bead ring not being 130

acted on by the rolls hereinbefore described is supported by idle rolls journaled at the rear of the table on axes which radiate from the same center as the arc of the circle on which the applicator and presser rolls are arranged.

My preferred manner of applying power to move the bead core and fabric strip through the machine is to have the shafts 10 of rolls 23 and 28 provided with bevel gears 30 and 31, respectively, which mesh with corresponding gears 32 and 33.

The shafts of these gears 32 and 33 carry spur gears 34 and 35 which in turn mesh 15 with spur gear 36 on shaft 37. A worm wheel 38 is connected with gear 36 so as to drive the same and worm 38 is in turn driven by worm 39 fast on shaft 40. Shaft 40 carries a flanged belt pulley 41 connected by 20 a loose belt with a pulley 42 fast on the shaft of an electric motor 43. Normally the belt is in a loose or slipping condition and to render it effective to drive the rolls through the connections described an idle 25 pulley 44 is provided carried by a pair of swinging arms 45 fast on shaft 46 which is adapted to be rocked to swing the idle pulley 44 against the belt to tighten the same by a treadle lever 47 which is connected by 30 adjustable link 48 with an arm 49 on shaft 46. A spring 50 tends normally to hold the treadle lever elevated.

From the foregoing description it is believed the operation of the machine will be 35 clearly understood but it may be briefly recapitulated as follows:

To cover a bead core it is laid in the groove of rollers 23 and 28 (supposing these rolls to already include members 23^a and 40 28^a of proper size) and pressed upon by idle rollers 28 and 29.

The guide roll 11 is position to hold the core in its natural circular path and if necessary, adjusted as to width of groove to 45 correspond to the bead to be covered.

If necessary also the flanges of drum 7 are adjusted or set to allow proper spacing of fabric on each side of the core and to 50 correspond to width of fabric used, and fabric guides are set to properly deliver or align the fabric strip. Idler roll 14 is set to start the bending up of the fabric from the toe or angle of the core so that it may enter the groove of roller 23 in a partially 55 folded up condition. The machine having been set in operation by the depression of the treadle lever roller 17, presses the core onto the fabric through the action of its presser spring, and, by reason of the sticky

or tacky nature of the material, "tacks" 60 the toe of the bead to the fabric. As the bead and fabric move forward, roll 24 co-acting with roll 23 causes the fabric, the wings or margins of which have been partially deflected upward (Fig. 5) to be 65 pressed against two sides of the bead (Fig. 6). Thereafter stitcher roll 27 deflects the margin 10^a (Fig. 7) across the upper face of the bead, to which it is firmly united, as well as to the projecting fabric margin 10^b 70 by the coaction of rolls 28 and 29.

Having thus described my invention, what I claim is:

1. In a machine of the class described, the combination with means for juxtaposing a traveling fabric strip and bead core, of a pair of coacting fabric pressing rolls, one of said rolls having a groove to receive said core and strip, said roll having a removable and interchangeable part forming one of 80 the walls of the groove.

2. In a machine of the class described, a roll comprising a main member having a face perpendicular to the axis of the roll and an axial extension and an auxiliary 85 member removably and interchangeably secured on said extension and having a reduced face forming, with said perpendicular wall, a bead receiving groove.

3. In a machine of the class described, a roll comprising a main member having a face perpendicular to the axis of the roll and a threaded axial extension, and an auxiliary member having a threaded bore 95 engaging said extension and having an annular reduced face forming with said perpendicular wall a bead receiving groove.

4. In a machine of the class described, a drum for supporting a traveling strip of fabric, means for juxtaposing thereto a triangular bead core with an angular edge towards the fabric and a flat side uppermost, a spring pressed cylindrical roller for bearing against said upper side, and means for subsequently folding the margins of the 100 fabric about the core.

5. In a machine of the class described, a drum for supporting a traveling strip of fabric, means for juxtaposing thereto a triangular bead core with an apical edge towards the fabric and the opposite side uppermost, a spring pressed cylindrical roller for bearing against said upper side, and means for subsequently folding the margins 110 of the fabric about the core.

In testimony whereof, I affix my signature.

FRED D. FOWLER.
